MODULATION SYSTEM

Andrew Alford, New York, N. Y., assignor to International Telephone Development Co., Inc., New York, N. Y., a corporation of Delaware

Application August 3, 1939, Serial No. 288,134

5 Claims. (Cl. 179—171.5)

My invention relates to radio beacons and more particularly to arrangements for coupling to radio beacon antennae to prevent intermodulation of signals.

In practice radio beacons are often arranged so that the antennae are energized over branch transmission lines from a signal carrier source. The different portions of the signal energy transmitted from each of the directive antennae are given a characteristic modulation by some means usually in the transmission line which alters the amount of energy transmitted to the antennae so as to produce a modulation. This modulation may be obtained by use of rotatable condensers or other forms of impedance changing devices in the lines feeding the antennae.

In these known types of systems, a common difficulty is that which may be termed cross-modulation. Thus when the impedance of one line is changed, not only does the current in the particular antenna to which it is connected become modulated, but the resultant load impedance is also varied so that some of the modulation is transferred to the other antenna. Similarly, the modulation in the second antenna is reflected into the first antenna so that there is quite an amount of cross-modulation. Since the modulation frequencies commonly used are in the order of 90 cycles per second and 100 cycles per second, the impedance cannot be coordinated with the minimums of desired wave, and the cross-modulation cannot be completely prevented. This results in a coarse beam which is less definite than would otherwise be obtained and is more subject to extraneous effects.

In accordance with my invention a balancing network is interposed between the source of energy and the transmission lines connected to the antennae to which the modulators are coupled, so that cross-modulation is prevented.

According to another feature of my invention, the network used for preventing cross-modulation is designed so as to provide for an optimum working condition so that a very small percentage of energy is wasted.

Other features and objects of my invention will be clear from the description of a preferred embodiment of my invention made in connection with the accompanying drawings, in which—

Fig. 1 diagrammatically illustrates an arrangement in accordance with my invention;

Fig. 2 diagrammatically illustrates a particular preferred embodiment of my invention, and

Figs. 3 and 4 illustrate modulation arrangements that may be utilized to attain these de-

sired results in accordance with the systems of my invention.

In Fig. 1, an energy source 100 is shown connected over a transmission line 101 to a network 5 indicated generally at 102. Network 102 is a special form of the high frequency bridge such as illustrated in my prior United States Patent No. 2,147,809 of February 21, 1939. This network is made in the form of reentrant loops having a 10 phase changing arrangement such as the transposition shown at 103. The network is formed with four arms of substantially equal electrical length so that the whole arrangement has the appearance of a bridge. At the intersection of 15 two of the arms, such as 104, 105, is connected the transmission line 101 and across the diagonally related junction of arms 107, 106 is connected a balancing network 108. This balancing impedance network has preferably an impedance substantially equal to the surge impedance of the load looking into it at the point of connection to the bridge. Across the other diagonally related junction point of the bridge network are connected transmission lines 110, 20 111, to the terminals of which are connected high frequency loads 112, 113, which may constitute directive antennae. At an intermediate 25 point on lines 110, 111, are connected modulators 114, 115, for giving to the energy transmitted over lines 110, 111, a characteristic modulation frequency.

When energy from source 100 is impressed upon the bridge, it is clear that so long as the impedance of loads 112, 113 together with the 30 transmission lines 110, 111 are equal, no energy is transmitted into the balancing impedance 108, because of the symmetrical relation. However, when modulators 114, 115 do not have the same effect on each line, the loads are not equal and 35 therefore some of the energy from source 100 is carried to the balancing network impedance 108. However, this change in impedance of load, for example, load 112, cannot be carried through to load 113 since the impedance of the source 100 and the balancing impedance 108 are equal and the network is therefore balanced with respect to this energy. It is therefore clear that with an arrangement of this type changes in the apparent load impedance due to the modulation cannot be reflected from one antenna to the other, and as a result cross-modulation is avoided.

Although the arrangement described above is primarily useful for systems wherein energy from a single source, characterized by different sig-

nals is to be transmitted to separate loads, the arrangement may also be used for transmitting from two separate sources placed in relative positions such as shown in loads 112, 113, connected to a single load arrangement at a point such as 101 without causing cross-modulation between the sources. This is clear from the general reciprocity law relating to such circuits.

Furthermore, where a simple balancing network is desired any desired form of phase shifting networks may be utilized in place of the transposition shown at 103. For example, an additional half wavelength of transmission line may be added, or any other well known form of phase shifter may be provided. These various forms of phase shifters are disclosed in my previously mentioned Patent 2,147,809.

In Fig. 2 is illustrated a preferred embodiment of my invention applied to a radio beacon circuit. In this arrangement the energy source 100 terminates in a tuned output circuit 200, which is coupled over a tuned secondary circuit 201 to transmission line 101. Arms 104, 105, 106, 107 of network 102 are each made equal to a quarter wavelength of the operating frequency or an odd multiple thereof in length. The network 108 has an impedance Z_0 equal to the surge impedance of the load looking into at point *a*. The four junction points of the bridge network are designated *a*, *b*, *c*, *d*, as shown. The modulating networks 114, 115 comprise sections of transmission line coupled to the antenna leads 110, 111 and provided with rotatable condenser plates 203, cut so as to give a different modulation to the energy transmitted from each of antennae 112, 113. When these networks are tuned by their respective condensers so as to be in resonance with the carrier frequency they act as cut-off filters producing an apparent open circuit in the line. A common driving motor 204 connected by means of a shaft, as shown by broken lines to the condenser rotors, serves to drive these condensers so as to modulate energy at two different frequencies, for example, at frequencies 90 and 100 cycles, respectively.

The impedance of loads 112, 113 as seen from points *b* and *d*, respectively, may be so related as to be equal to one-half Z_0 . Then, since arms 104, 105 are quarter wavelength lines, the impedance at point *a* will be twice the surge impedance of line 101 or $2 Z_0$. Thus, since Z_0 is working in two branches in parallel, an impedance match between the source and the load is provided. If then, the modulating arrangements are located at such a distance from the junction points *c* and *d*, that the portion of the lines 110, 111 between points *c* and *d* and the modulator point, where the apparent open circuit occurs when the networks are tuned to stop the flow of current in lines 110, 111 is made equal to an odd multiple of a quarter wavelength. The following operational characteristics will be observed:

At the time loads 112, 113 are drawing the same amount of power there will be a node at point *c*, so that the arms 106, 107 will be equivalent to a pair of short circuited quarter wavelength lines hung on the load, and no effect upon the impedance of the circuit will be caused thereby. Therefore, at this time no current will flow into network 108 and no energy will be consumed therein. At the time that neither antenna 112 or 113 are drawing any power, that is, when both are effectively open circuited, by modulators 114, 115, the network 102 is completely balanced and no energy will be dissipated in network 108.

Under the conditions of the worst unbalance, that is, when for example, network 114 is tuned so as to transmit no energy to antenna 112 and the energy transmitted to 113 is maximum, the following results are noted. Since network 114 produces an effective open circuit in line 110, junction point *b* is bridged by an open quarter wave section of transmission line. This open quarter wave line has the same effect with respect to the energy as if a short circuit were placed across the network at point *b*. Therefore, arm 104 acts as a short circuited quarter wave transmission line across point *a*, and offers substantially infinite impedance to energy, so that all of the energy from source 101 flows into arm 105. At the same time arm 107 acts as a short circuited quarter wavelength line across point *c* and does not effect the impedance network. Since antenna 113 and transmission line 111 has an effective impedance equal to one-half Z_0 and a network 108 has an impedance of Z_0 , two-thirds of the energy from source 101 will be transmitted to antenna 113 and only one-third of the energy will be dissipated in impedance 108.

Since the times at which this worst condition will arise are not very frequent, an arrangement such as shown in Fig. 2 with the optimum dimension will dissipate only from 6% to 12% of the energy. In any case where such precautions are not taken, the worst condition will result in half of the energy being dissipated in network 108, at the time antenna 112 or antenna 113 is carrying all of the load. Even this arrangement will produce a relatively small dissipation of the total power from the transmitter. Thus, although the arrangement according to my invention results in a certain amount of waste power, this is not a very important factor when it is considered that if modulating tubes are used inefficient couplings must be provided in order to reduce cross-modulation, resulting also in a waste of power. Furthermore, in these other types of arrangements a complete balancing of the circuit and elimination of cross-modulation cannot be achieved, as it can in accordance with my invention.

By utilizing the arrangement with the optimum operating characteristics as described in connection with Fig. 2, and also providing that the transmission line 101 is made equal to a quarter of a wavelength or odd multiple thereof, further advantages may be achieved.

When both 114, 115 are tuned so that the full amount of power is being utilized in the antenna, a complete transfer of energy occurs. Similarly, when one antenna is effectively open circuited and the other is fully loaded, the full energy transmission from source 100 is taking place.

When the condition occurs so that neither antennae 112 or 113 are drawing any power from the load, an effective short circuit across network 102 at *c* and *d* occurs. Since 101 is equal to an odd number of quarter wavelengths, and also arms 104, 105 are equal to an odd number of quarter wavelengths, this makes the total effect of transmission line 101 and arms 104, 105 equivalent to a short circuited half-wave transmission line. This is equivalent to a short circuit across terminal 210 of the tuned secondary circuit 201. Since 201 is tuned to the operating frequency when the effective short circuit is made, the system presents a high impedance to the energy so that it is the same as though the oscillator were working into a very high impedance load. For this reason, the energy dissipated from the output 200 at this time will be smaller

than at any other position of the modulation cycle. Thus, it is possible to use a higher plate potential on the output of the source than would otherwise be possible if at the time the actual load were reduced to substantially zero, the impedance in the output also was reduced. With an arrangement of this type higher plate voltages and therefore higher power output of the system may be utilized so long as continuous modulation is provided. However, in operating in this manner the arrangement must at all times be provided with the proper load circuit arrangement. Otherwise, if the system were permitted to attain such a position that a low output impedance was provided at any time, the oscillator would carry such high current as to probably result in a burning out of the oscillator.

For the purpose of providing the system transmission arrangement such as described in connection with Fig. 2, the modulation arrangement must be of a type which will produce an effective opening of the circuit of lines 110, 111, so that the total impedance of either load varies between zero and

$$\frac{Z_0}{2}$$

For this purpose several types of arrangements may be utilized. In Figs. 3 and 4, I have illustrated two types of arrangements suitable for use in this arrangement. Referring first to Fig. 3, two transmission line conductors 301, 302 are shown. These may be the conductors of a line such as 110, 111 of Figs. 1 and 2. Mounted close to these transmission line conductors is provided a transmission line section 303, closed at one end and open circuited at the other. When such a transmission line section is coupled to a transmission line and tuned to the frequency of the system, the network will operate as a substantial cut-off network, that is, substantially no energy will pass the ends of the network. However, when the network is even very slightly detuned from the operating frequency, it will have substantially no effect upon the transmission of currents to the line. Other forms of coupled networks may be used, the principles of such networks being more fully set forth in my United States Patent 2,159,648 of May 23, 1939. To perform the desired modulation arrangement a network such as shown at 307 is mounted close to 301, 302 so as to be coupled thereto, and between the open ends of this section I provide a rotatable condenser plate 330. This condenser plate is provided with a plurality of notches, so that as the plate is rotated section 307 will be periodically tuned and detuned from the operating frequency. The frequency of the modulation signals may be determined by the speed of rotation of the condenser disc 330, and the number of notches provided therein. Thus, any desired modulation frequency may be produced. For mounting this arrangement it is convenient to provide a trough section such as 308 mounted around the transmission line conductors and carrying the shaft of the rotatable condenser. In order to prevent disturbances of the system by means of dirt accumulation, and so forth, a cover plate may be provided over the trough 308.

In Fig. 4 is shown another type of arrangement for producing the desired modulation effect. A section of transmission line 41 is bridged across the transmission lines 301, 302, at a point preferably an integral multiple of a half wavelength from the junction of the bridge arm. 75

This network may be tuned to the operating frequency and detuned therefrom. When properly tuned it may operate so as to produce a virtual short circuit across the transmission line. Since, as stated above, this section may be spaced at a distance equivalent to a half wavelength from the junction point of the bridge arm and may be made equal to a half wavelength long, it is clear that at this time the effect will be the same as though the transmission line were short circuited at a point a half wavelength distant from the junction. This will be effectively equivalent to a short circuit at the junction point, for example, at a point such as b in the arrangement shown in Fig. 2.

Although I have illustrated only two forms of modulation circuit for use in the arrangement in accordance with my invention, it is clear that any suitable tuning networks may be provided, it being necessary that the system be arranged so that the load varies from zero up to its maximum amount of

$$\frac{Z_0}{2}$$

25 For this purpose other known types of networks, such as combinations of inductance and capacities may be utilized in place of the picture arrangements I have shown. However, the illustrated arrangements are generally more easily constructed and are generally more accurate to use for ultra-high frequencies and for this reason are preferable in the higher frequency ranges.

Although I have illustrated my invention in connection with certain preferred embodiments thereof, it should be distinctly understood that these illustrations are merely by way of example. The cross-modulation prevention arrangement may be utilized with any desired type of high frequency energy load.

40 What I consider to be my invention and upon what I desire to secure protection is embodied in the accompanying claims.

What I claim is:

45 1. A high frequency system comprising a reentrant loop circuit, a high frequency energy source having a given surge impedance coupled to a point on said reentrant loop circuit, a network having substantially the same impedance as said surge impedance coupled to said loop circuit at another point, said coupling points dividing said loop into two parts, one of said parts being electrically a half wavelength or an odd multiple of a half wavelength longer than the other of said parts, high frequency loads of substantially equal impedance values coupled to said loop substantially midway between the points of connection of said source and said network, and means for differently modulating the energy delivered from said source to respective ones of said loads.

50 2. A high frequency system according to claim 1, wherein said arms of said reentrant loop formed by connection of said source, said loads and said impedance are each electrically a quarter wavelength or an odd multiple of a quarter wavelength at the operating frequency.

55 3. A high frequency transmission system comprising a source of energy, two loads for receiving energy from said source, modulating means for imparting to energy delivered to said loads different modulating characteristics, and means for interconnecting said source and said loads to prevent intermodulation, comprising a reentrant loop circuit, means connecting said source to

said loop circuit at a fixed point and a high frequency impedance network having an impedance substantially equal to the impedance of said source connected at another point of said loop, said connecting points dividing said loop into two parts, one of said parts being electrically substantially a half wavelength or an odd multiple thereof longer than the other of said parts, and means for connecting each said load to said loop at points substantially equi-distant electrically between the points of connection of said source and said impedance network.

4. A high frequency transmission system comprising a source of high frequency energy, two high frequency loads of substantially equal impedance, a network for interconnecting said source and said loads and providing a conjugate relationship between said loads comprising, a re-entrant bridge circuit having four arms of substantially equal electrical length, one of said arms having transposition therein, means for coupling said source to the junction point of two of said arms, a high frequency impedance

means, means for coupling said impedance means to the junction point of said bridge circuit diagonally related to said first named junction, means for coupling said loads respectively to the other junctions of the arms of said bridge, and means for modulating differently the energy delivered to said loads.

5. A high frequency transmission system according to claim 4, wherein the arms of said re-entrant bridge circuit are each equal to a quarter wavelength of the operating frequency or an odd multiple thereof, said means for coupling said loads to said bridge each comprising transmission line sections, and said modulating means each comprising arrangements for varying the impedance of the transmission line from normal value to a very high impedance value, said modulating means being located at a point in said transmission line a quarter of a wavelength or an odd multiple of a quarter wavelength from the connection point of said load coupling means and said bridge.

ANDREW ALFORD.
